UNITED STATES PATENT OFFICE.

CLARENCE O. WHITE, OF MINNEAPOLIS, MINNESOTA, ASSIGNOR OF ONE-HALF TO EDWARD J. KIMBALL, OF MINNEAPOLIS, MINNESOTA.

VAPORIZER FOR EXPLOSIVE-ENGINES.

SPECIFICATION forming part of Letters Patent No. 694,708, dated March 4, 1902.

Application filed February 11, 1898. Serial No. 669,912. (No model.)

To all whom it may concern:

Be it known that I, CLARENCE O. WHITE, of the city of Minneapolis, county of Hennepin, State of Minnesota, have invented certain new and useful Improvements in Vaporizers, of which the following is a specification.

This invention relates to explosion-engines, and particularly to vaporizers therefor, whereby a suitable mixture of hydrocarbon and air may be obtained.

The object of the invention is to provide a vaporizer the operation of which will be reliable and sure and will depend upon the partial vacuum created in the cylinder of the engine by the retirement of the piston therein.

The invention consists generally in the combination, with an engine-cylinder and its piston, of a mixing-chamber having an opening into the cylinder and provided with an air-inlet opening, a valve normally closing said air-inlet opening and adapted to resist the entrance of air therethrough to a limited extent, said mixing-chamber provided with an air-inlet opening intermediate between said valve and the cylinder, and means for supplying oil at a point near said intermediate opening, whereby the suction of air through said opening will exhaust the oil from the air-duct and discharge the same into said mixing-chamber.

The invention further consists in various constructions and in combinations of parts, all as hereinafter described, and particularly pointed out in the claims.

The invention will be more readily understood by reference to the accompanying drawings, forming part of this specification, and in which—

Figure 1 is a vertical section of a vaporizer or carburetor embodying my invention. Fig. 2 is a vertical section of a modified form thereof, wherein the main check-valve is dispensed with. Fig. 3 is a horizontal section substantially on the line $x-x$ of Fig. 2.

As shown in the drawings, 2 represents the cylinder of a gasoline or other explosion engine, wherein the piston is driven by the explosion of air with petroleum, gasoline, or the like. Upon the side or end of the cylinder is the mixing-chamber 3, having an opening 4 into the cylinder. The mixing-chamber com-

prises the two parts 3 and 3', the latter being provided with an air-inlet opening 7 in its lower end. 5 indicates a check-valve adapted to be seated by the back pressure from the latter to prevent the escape of the gases therefrom. In the lower part of the portion 3' of the chamber is a valve 6, which is automatically operated and possesses a sufficient weight to slightly oppose the passage of air therethrough. At one side of the mixing-chamber is a reservoir 8, supplied with gasoline or other oil through a pump-pipe 9.

10 is an overflow-pipe, and the oil is always kept at the level of the top of the overflow-pipe, so that there is a given head of oil always present in the reservoir.

At one side of the reservoir 8 is a duct 11, having a small opening 13 into the lower part of the reservoir beneath the surface of the oil therein. The duct 11 leads upward and connects with a horizontal duct 14 of such a size as to allow the passage of only a very small stream of oil. The flow of oil through the duct is controlled by a pin-valve 12. The duct 14 preferably discharges through a small nozzle 15 into the mixing-duct 16, which extends to or opens into the chamber 19 between the two valves 5 and 6. The end of the duct 16 is preferably extended downwardly, as shown, opposite the nozzle 15 in order that the stream of oil from the nozzle may be broken up to insure its mixture with the air which enters through the opening 17 in the duct 16. This opening 17 is preferably opposite the nozzle 15, and the air rushing across the nozzle operates to siphon the oil therefrom. A pipe 18, extending from an opening or channel in the cylinder, may be connected with the opening 17 to supply the hot air thereto. To prevent back pressure from the space 19, I prefer to arrange a small gravity-valve 20 to normally close the duct 16.

The operation of this device is as follows: When the piston travels forward in the cylinder, a partial vacuum will be created and the air will rush through the opening 7 and raise the valves 5 and 6; but being somewhat resisted by these valves a proportionately-greater body of air will enter through the opening 17 opposite the nozzle 15 to draw the oil upward from the reservoir 8 and discharge

it, with such air, into the duct 16. This current of air will open the valve 20, and the heavily-charged air from the duct 16 will pass into the space 19, where it will mix with the 5 larger body of fresh air and will be carried upward through the valve 5 and into the cylinder. Upon the backward or compression stroke of the piston the valve 5 will be automatically closed, as will also the valves 6 and 10 20, thereby preventing the escape of the gases from the cylinder and also preventing back pressure through the duct 16, which back pressure will operate to force back the oil in the duct 15 and prevent the supply of oil for 15 the next succeeding charge to the cylinder.

The nozzle 15 is not essential to the operation of the device, nor is the valve 5 necessary. This I have indicated in Figs. 2 and 3, where it will be seen that the valve 5 is omitted and 20 the valves 6 and 20 are depended upon to prevent the escape of the gases from the cylinder. I prefer, however, to use two valves 5 and 6, the valve 5 preventing the filling of the space 19 with dead gases after an explosion. The 25 duct 16', Figs. 2 and 3, may be a straight duct, and the air opening or openings 17' may enter at right angles to both the duct 16' and the oil-supply duct 14'. The rush of air before the duct 14' will operate to suck the oil 30 from said duct and the reservoir 8.

The device illustrated is most simple in its construction and cannot readily get out of order. The flow of oil is easily controlled, and, furthermore, the oil-feed is entirely automatic with respect to and is proportionate 35 to the work required of the engine.

The vaporizer may be advantageously employed with any type of explosion-engine.

Having thus described my invention, I 40 claim as new and desire to secure by Letters Patent—

1. In a vaporizer for an explosion-engine, the combination, with the cylinder, of the mixing-chamber 19, provided with the air-inlet in its lower part and having in its upper part a port leading into said cylinder, valves provided in said inlet-opening and said port, to be closed by back pressure from said cylinder, the valve of said inlet being 45 smaller than of said port, the overflow-reservoir 8, the gasoline-inlet, and the overflow-pipes connected therewith, the valve-controlled upwardly-extending duct in said reservoir, the horizontally-extending mixing-duct 50

16, also therein and larger than said gasoline- 55 duct, said mixing-duct communicating with said chamber 19, as and for the purpose specified.

2. The combination, with the valve-chamber provided with a back-check air-valve, of 60 the gasoline-reservoir wherein the gasoline is maintained at an even level, a duct 11 extending upwardly therefrom, a valve therein, a vapor-duct 16 connecting the same with said valve-chamber, and a transverse air-opening in said vapor-duct adjacent to the discharge-point of the duct 11 from said reservoir, said vapor-duct having a downwardly-extending portion intermediate between the reservoir-duct and said valve-chamber, and 70 provided with a back-check valve, substantially as described.

3. The combination, of the valve-chamber provided with the back-check valve 6 and having the air-inlet opening 7, with the reservoir 8, having inlet and outlet pipes 9 and 10, and also provided with the ducts 11 and 14, the horizontal nozzle 15, the vapor-duct 16 into which the same projects, and said vapor-duct having a back-check valve and being 80 provided with an air-opening 17 opposite said nozzle through which a small quantity of air is admitted for initial mixture with the liquid drawn from said duct 14, substantially as 85 described.

4. In a vaporizer for an explosion-engine, the combination, with the cylinder, of the mixing-chamber provided with the air-inlet in its lower part and having in its upper part a port leading into said cylinder, valves 5 and 90 6 provided respectively in said port and said inlet-opening to be closed by back pressure from said cylinder, the reservoir 8, the gasoline-inlet, the duct 11 communicating with said reservoir, the horizontal duct 14 communicating with said duct 11 the mixing-duct 16, the air-inlet opening 17 leading into said duct 16, and the gravity-valve 20 provided in the space between said port and said inlet-valves and adapted to normally close said 95 duct 16, substantially as described.

In testimony whereof I have hereunto set my hand, this 5th day of February, 1898, at Minneapolis, Minnesota.

CLARENCE O. WIIITE.

In presence of—

C. G. HAWLEY,
RICHARD PAUL.
